THRASHING MACHINE

Filed Feb. 29, 1928

UNITED STATES PATENT OFFICE

DETTRICH ERNEST HUMBKE, OF WETASKIWIN, ALBERTA, CANADA

THRASHING MACHINE

Application filed February 29, 1928, Serial No. 257,982, and in Canada January 27, 1928.

This invention relates to improvements in thrashing machines and more particularly to an improved foldable divide board for thrashing machines, and the objects of the invention are to provide a simply constructed and durable divide board adapted to fit in the centre of the feeder of a thrashing machine.

Under existing conditions it requires two individuals to place the divide board in position in the feeder, one climbing to the top of the separator and another standing at the front of the feeder. With my invention this duplication and consequent waste of time and labour is eliminated, the divide board being placed in position simultaneously with the feeder in one operation.

With the foregoing and other objects the novel features of the invention include a divide board formed with a hinged section coordinating with the hinged section of the feeder and operable therewith whereby the divide board is simultaneously placed in position with the feeder.

Referring now to the drawings in which like characters of reference indicate corresponding parts in each figure.

Figure 1 is a side elevation of a portion of a thrashing machine showing the feeder and the divide board partially broken away and in dotted lines in folded position.

Figure 2 is a top plan view of Figure 1.

Figure 3 is an enlarged sectional detail of the hinged connection of the divide board, 35 on the line 3—3 of Figure 1.

Figure 4 is an enlarged section on the line 4—4 of Figure 1.

Fig. 5 is a fragmentary side elevation of the divide board in open position.

Referring now more particularly to the drawings in which a preferred example of my invention is disclosed, A indicates a portion of a thrashing machine of well known construction and 10 a feeder also of well known construction and formed in two sections 11 and 12 hingedly connected to one another as at 13. Centrally and longitudinally of the feeder is the essential feature of my invention, namely, the divide board 14 formed in two sections 15 and 16, the section

16 being connected as at 17 to the rod 18 bolted to the frame as at 19 and the section 15 being hinged as at 20 with a hinge 21 provided with a lap 22 to prevent anything engaging therewith. The hinge 21 is in the form of a skeleton channel member and is adapted to partially encase the ends of the sections 15 and 16 on the lower edge thereof when in closed position. This channel member is pivotally connected at either end to U shaped reinforcing strap members 28 rigidly secured to the divider board and extending around the top and either side thereof. A U shaped housing member 29 is secured to one end of the section 16 and is adapted to extend over the top and partially down either side thereof to meet the channel member when in closed position, and is formed with a protruding portion which is adapted to house the end of the section 16 when the divide board is in closed position thus ensuring a completely encased joint.

A plate 23 engaging on each side of both sections of the divide board and associated with the hinge 21 is provided. This plate is adapted to rigidly hold the divide board securely in operative position. In the outer end of the divide board is a slot 24 and on the outer end of the feeder is a forked member 25 for the divide board to rest in by means of a bolt 26 extending through the forked member into the slot 24 to retain the hinged section 15 of the divide board and the divide board together when swung into position, as illustrated in dotted lines in Figure 1, when both sections may be hooked up to the thrashing machine as at 27.

It will thus be seen that when the feeder is placed in position that the divide board will simultaneously be placed in position thus avoiding all extra trouble while at the same time ensuring more efficient operation of the device.

As many changes could be made in the above construction and many apparently widely different embodiments of my invention, within the scope of the claim, constructed without departing from the spirit or scope thereof, it is intended that all matter contained in the accompanying specification

and drawings shall be interpreted as illustrative and not in a limiting sense.

What I claim as my invention is:

In a divide board for thrashing machines,
5 the combination with a foldable feeder pro-
vided with a frame, of a divide board formed
of two sections, a rigidly mounted section
and a moveable section, adapted to be con-
nected by a hinge, said hinge comprising a
10 skeleton channel member adapted to partially
encase the ends of the sections each end of
said channel member being pivotally con-
nected to a reinforcing U shaped strap mem-
ber rigidly secured to the divide board on
15 either side of the meeting ends of the two
sections said U shaped strap members ex-
tending around the top and sides of either
section, a U shaped housing member secured
to one end of the moveable section and formed
20 with a portion protruding therefrom, said
protruding portion being adapted to house
the meeting end of the rigidly mounted sec-
tion when in working position, the opposite
end of the moveable section being provided
25 with a slot, a forked member having a bolt
extending therethrough and adapted to slide
in said slot, said forked member being rigidly
secured to the feeder whereby on the feeder
being swung into operative or folded posi-
30 tion, the divide board is similarly swung.

In witness whereof I have hereunto set my
hand.

DETTRICH ERNEST HUMBKE.
